UNITED STATES PATENT OFFICE.

CHARLES C. BLAKE, OF BROOKLINE, MASSACHUSETTS, ASSIGNOR TO C. C. BLAKE,
INCORPORATED, OF BOSTON, MASSACHUSETTS, A CORPORATION OF NEW YORK.

ADHESIVE JOINT.

1,284,860.

Specification of Letters Patent. Patented Nov. 12, 1918.

Application filed November 13, 1915. Serial No. 61,382.

To all whom it may concern:

Be it known that I, CHARLES C. BLAKE, a citizen of the United States, residing at Brookline, in the county of Norfolk and 5 State of Massachusetts, have invented a new and useful Improvement in Adhesive Joints, of which the following is a specification.

The present invention relates to adhesive joints by means of which separate pieces of 10 material are connected.

In the adhesive joint devised by me one of the pieces to be joined is coated with a normally cold adhesive in which a wire of heat-producing resistance is embedded. 15 When the other piece of material is pressed against the coated face of the first piece a current of electricity is passed through the wire. The wire soon becomes red hot thereby rendering the adhesive tacky and 20 sticking the pieces of material together. As the wire employed is very fine for many uses it may remain in the joint with safety. For other purposes it may be desirable or expedient to remove the wire from the joint.

25 The object of the present invention is the production of an adhesive joint from which the source of heat may be removed without affecting the joint.

To the accomplishment of this object, and 30 such others as may hereinafter appear, the features of the present invention relate to certain devices, combinations and arrangements of parts, hereinafter described and then set forth broadly and in detail in the 35 appended claims, which possess advantages readily apparent to those skilled in the art.

The various features of the present invention will be best understood from an inspection of the accompanying drawings 40 illustrating the best form of the invention at present known to the inventor, in which,

Figure 1 is a plan of an insole for a welt shoe which is to be connected to an upper;

Fig. 2 is a lateral sectional elevation of 45 an insole having a groove formed along its edge face;

Fig. 3 is a similar view showing the groove filled with a normally cold adhesive and having a wire embedded therein; and

50 Fig. 4 is a lateral sectional elevation of a lasted welt shoe.

Referring now to the drawings an insole 1 is provided with a groove 2 (Fig. 2) along its edge face which is filled with a coating

3 of jewelers' cement, sealing wax or some other of the well known normally non-tacky adhesives all of which are non-conductors. Embedded in this coating is a conductor 4 (Fig. 1) hereinafter termed a thermal conductor, for transmitting force, such as heat 60 or electricity. While the thermal conductor may be a tube for transmitting steam, hot air or other heating medium it is preferred to employ a wire of heat-producing resistance for conducting electricity. The insole 65 is secured to a last in the usual way, or in accordance with the method described in application for Letters Patent of the United States filed by me September 16, 1915, Serial No. 51,099, and an upper 5 is then up- 70 drawn in the manner illustrated in Fig. 4. The updrawn upper is then firmly pressed against the grooved edge face of the insole and a current of electricity passed through the wire 4. As the wire has a high resist- 75 ance it soon becomes red hot whereupon the coating 3 is rendered tacky thus making a tight joint between the insole and upper. With this adhesive joint the heat is applied directly to the contacting faces of the parts 80 to be joined thus obviating all danger of damage resulting to the material of the parts. While the adhesive is hot the wire may be withdrawn without affecting the joint between the upper and insole. 85

While the illustrated embodiment of the present invention is directed to an improved adhesive joint for connecting the upper and sole of a shoe it is not to be understood as limiting the scope of the claims, where 90 the context otherwise permits, to the exclusive use of the adhesive joint in the manufacture of shoes as it will be apparent to those skilled in this and other arts that the adhesive joint herein disclosed may be 95 advantageously employed in the manufacture of many kinds of articles.

It will be clear to those skilled in this art and with the general objects of the present invention in view, that changes may be 100 made in the details of structure, the described and illustrated embodiment thereof being intended as an exploitation of its underlying essentials, the features whereof are definitely stated in their true scope in the 105 claims herewith.

What is claimed as new, is:—

1. In combination, two members having

interposed therebetween an adhesive which is normally non-adhesive but which is rendered tacky under the influence of heat, and a thermal conductor for heating the adhesive and removable from between the members while the adhesive is hot, substantially as described.

2. A sole provided with a groove formed in its edge face, an adhesive filling which is normally non-adhesive but which is rendered tacky under the influence of heat in the groove, and a thermal conductor embedded in the adhesive, substantially as described.

3. An insole having a longitudinal groove formed along the median line of its edge face which is straight vertically and ar-

ranged normal to the parallel faces of the insole, substantially as described.

4. A sole provided with a groove in its edge face, an adhesive filling which is normally non-adhesive but which is rendered tacky under the influence of heat in the groove, and a thermal conductor embedded in the adhesive and arranged longitudinally 25 of the groove, substantially as described.

5. An adhesive joint comprising two members having an adhesive between their contacting faces and a heating element between the members for heating the adhesive and removable from between the members while the adhesive is hot, substantially as described.

CHARLES C. BLAKE.
